CLAIM

The ornamental design for a puck member for fidget accessory, as shown and described.

DESCRIPTION

FIG. 1 is a top perspective view of a puck member for fidget accessory according to the present invention;

FIG. 2 is a bottom perspective view thereof;

FIG. 3 is a front view thereof;

FIG. 4 is a rear view thereof;

FIG. 5 is a left side view thereof, the right side view being a mirror image of the left side view;

FIG. 6 is a top view thereof;

FIG. 7 is a bottom view thereof;

FIG. 8 is a cross-sectional view thereof taken along cross-section indicators 8-8 in FIG. 4.

The broken lines illustrate portions of the puck member for fidget accessory that form no part of the claimed design.

1 Claim, 4 Drawing Sheets
